APPARATUS FOR CONDITIONING AIR

Bert E. Mills, Oak Park, Ill., assignor to Mills Novelty Company, Chicago, Ill., a corporation of Illinois

Application September 24, 1934, Serial No. 745,175

8 Claims. (Cl. 62—91.5)

This invention relates to an improved apparatus for conditioning air, and particularly to an apparatus for cooling, and regulating the moisture content of, the air to be treated, by the 5 use of a solidified refrigerant such as carbon dioxide.

One of the important objects of the invention is to provide an apparatus for efficiently utilizing a refrigerant, such as solidified carbon dioxide, 10 for the cooling of air in offices and similar places where it would not be practical or feasible to use a costly compressor-condenser type of refrigerating equipment.

Another object of the invention is to provide 15 an air conditioning apparatus wherein a mass of solidified refrigerant, such as carbon dioxide, is efficiently utilized to cool the air through the provision of a plurality of air flow tubes which are submerged in a body of liquid which is maintained in contact with the mass of refrigerant, the liquid, by reason of its complete contact with 20 the exterior surfaces of said tubes, providing an almost perfect medium for transfer of heat between the walls of the tubes and the mass of refrigerant.

Another object of the invention is to provide 25 a cooling apparatus of the character set forth in which the cooling tubes through which the air is circulated are arranged to operate as condensers for removing moisture from the air during the course of its passage through the tubes, thereby reducing the humidity of the air in the 30 room as well as cooling the same to a comfortable degree.

A further object of the invention is to arrange 35 the cooling tubes in such position that the moisture forming therein will be drained from the tubes and automatically removed from the path of air flow.

A still further object of the invention is to 40 provide in an air conditioning apparatus of the type specified, means for regulating the extent to which the mass of refrigerant is immersed in the body of liquid, thereby adapting the apparatus to variations in the rate of cooling, depending upon the volume of air being treated.

Other objects and advantages of the invention 45 will be apparent from the following detailed description taken in connection with the accompanying drawings wherein I have shown the preferred form in which I have thus far contemplated applying the principles of the invention.

Referring to the drawings:

Fig. 1 is a front elevational view of a cabinet

embodying the improved air conditioning apparatus, portions of the front wall of the cabinet being broken away to show the construction of the cooling tubes and the liquid level adjusting mechanism;

Fig. 2 is a top plan view of the cabinet, the top wall of the cabinet being broken away to show the construction of the inner top wall;

Fig. 3 is a horizontal section through the cabinet taken on line 3—3 of Fig. 1; and

Fig. 4 is a vertical section through the cabinet taken on line 4—4 of Fig. 1.

Referring to the drawings in detail, the apparatus in the embodiment shown is embodied in a double walled cabinet consisting of a rectangular base 5, a pair of spaced front walls 6 and 7, a similar pair of spaced back walls 8 and 9, side walls 11 and 12 extending between the inner pair of walls 7 and 9, and outer side walls 13 and 14 extending between walls 6 and 8 and 20 spaced from walls 11 and 12, respectively. The space between the inner and outer vertical walls of the cabinet is filled with a body of insulating material 15 such as Dry Zero, or the like. The bottom of the cabinet, which is supported directly on base 5, is closed by a pair of metal walls 16 and 17, the space between these walls being similarly filled with a body of insulating material 18.

The several walls of the cabinet are suitably 30 joined to form liquid-tight joints, and the upper edge portions of the inner vertical walls are flanged outwardly as indicated at 19, these flanged portions being either welded or riveted to the adjacent upper edge portions of the outer 35 walls. The packing of insulating material is thus completely enclosed and serves to effectively prevent transmission of heat to the interior of the cabinet.

In accordance with my invention I provide 40 in the cooling cabinet a plurality of air flow tubes 21 which are preferably formed of sheet metal. As shown in Fig. 4, these tubes extend between walls 7 and 9, the ends of the tubes being welded as indicated at 22 to the circumferential edges of openings which are formed in walls 7 and 9 to receive the ends of the tubes. The portions of the outer vertical front wall 6 which register with the ends of tubes 21 are cut away to provide openings 23, and the lower portion of back wall 8 opposite the bank of tubes 21 is cut away to receive a fan jacket 24 which is riveted at 20 to wall 8. Air is circulated through tubes 21 by a fan 25 which is driven by an electric motor 26, the latter being remov- 55

ably secured by a series of bolts 27 to casing 24, said casing being provided with openings 28 through which air may pass to the tubes 21. If preferred, the blower unit consisting of fan 25 and motor 26 may be made entirely separate from the cabinet. In fact an ordinary electric fan may be used for this purpose by merely placing it opposite the tube openings in rear walls 8 and 9.

10 The apparatus is designed to cool the air during its passage through tubes 21 under the action of fan 25. In the embodiment shown I employ a mass of solidified carbon dioxide 29 which is supported in the cabinet above tubes 21 on a screen 31, the latter being supported in the cabinet on a pair of angle bars 32 and 33 which are secured to walls 7 and 9, respectively. In accordance with one of the important features of the invention, the mass of solidified carbon dioxide or dry ice 29, instead of being placed in direct contact with tubes 21, is supported in the upper portion of the cabinet, as shown in Figs. 1 and 4, and a path for flow of heat from the walls of tubes 21 to the mass of refrigerant 29 is provided by a body of liquid 34 which extends from the bottom of the cabinet to level slightly above screen 31. The purpose of this liquid is to provide for a more perfect path for flow of heat through the walls of tubes 21 to the mass 30 of refrigerant than would be obtainable if the refrigerant were simply placed in direct contact with the exterior walls of said tubes. In the case where dry ice is employed as the refrigerant, I find that denatured alcohol is a suitable liquid 35 to use for this purpose. In general it may be said that the liquid used must be one which has a freezing point below the melting point of the particular refrigerant employed. Also the liquid should be one in which the refrigerant will readily dissolve.

An apparatus of this type, which uses an expendable refrigerant, must necessarily be designed to operate for a period of several hours, or possibly a day, without requiring replenishment of the refrigerant. In the embodiment shown, in which the apparatus is especially designed for the use of dry ice, I find that most efficient use of the refrigerant is obtained by adjusting the level of liquid 34 so that it has but very slight contact with the mass of refrigerant, it being noted from Figs. 1 and 4 that the surface of the liquid 34 is but slightly above screen 31. As previously explained, the body of liquid serves as a cooling bath for extracting heat from the walls of tubes 21, and it is usually unnecessary to have any substantial portion of the mass of refrigerant immersed in the liquid.

At ordinary pressures solidified carbon dioxide vaporizes without passing through the intermediate liquid stage. The carbon dioxide gas is removed from the cabinet through a vent pipe 35 which is positioned in the upper portion of the rear wall of the cabinet. The top of the cabinet is closed by a sheet metal cover plate 36, and an inner cover plate 37, formed of suitable insulating material, is provided for sealing the refrigerant compartment, this cover being provided at its rear edge with a pair of cleats 39 which are received in sockets formed in the rear wall of the cabinet. The front edge of cover 37 is provided with sliding latch members 41 which are secured in position by channel strips 42. The cover 37 is locked in position by inserting cleats 39 in the rear cabinet wall after which the sliding latch members 41 are moved outwardly into

locking position against the front wall as shown in Fig. 2.

By locating the vent tube 35 at the top of the refrigerant chamber (the space defined by walls 9, top 36, and screen 31), and keeping the latter 5 covered, a blanket of vaporized carbon dioxide is constantly maintained around the entire body of unmelted refrigerant, insulating the same from such heat as may find its way to the inner walls 9. At the same time, the excess (and least cold) 10 carbon dioxide is allowed to flow off, while the colder portion of the carbon-dioxide blanket, remains in the chamber.

By maintaining the body of solid refrigerant completely above and spaced from, the air tubes 15 21, it is possible to use solid cakes of the refrigerant of large enough size to fill the refrigerant chamber, and the conduction of heat thereto from all of the tubes 21, will be uniform. This is of particular importance in connection with 20 the use of carbon-dioxide ice, because of the great difference between the vaporizing temperature of the latter and the temperature to which the air is to be cooled. It is undesirable to have direct contact between the air-flow tubes and the 25 solid refrigerant. Maximum cooling efficiency can be obtained by cooling all of the tubes to uniform temperature, keeping the body of solid refrigerant insulated from heat absorption by the enveloping blanket of carbon-dioxide gas above 30 it and on all sides, and limiting its heat absorption to the contact of its bottom with the liquid which carries the heat uniformly from all of the tubes.

Means for varying the extent of immersion 35 of the mass of dry ice 29 in the liquid 34 is provided whereby to regulate the container to the cooling of a greater or less volume of air as may be desired. In the embodiment shown I provide for this adjustment through the use of a liquid 40 displacement panel 43 which is suspended adjacent a side wall of the cabinet by a pair of cables 44 which are wound upon a shaft 45, the latter being positioned near the top of the cabinet and journaled at its opposite ends in walls 7 and 9. 45 Shaft 45 is provided at one end with a worm wheel 46 which meshes with worm gear 47, the latter being mounted on a crank 48 which projects from the side wall of the cabinet. By turning crank 48, panel 43 may be raised or lowered 50 in the body of liquid 34, thereby changing the liquid level to regulate the extent of immersion of the mass of dry ice 29. If air is being circulated through tubes 21 at a comparatively rapid rate, it may be desired to have the mass 55 of refrigerant 29 immersed to a considerable extent in liquid 34. On the other hand, if the cooling demand is comparatively light, panel 43 may be raised to produce a correspondingly lower liquid level and a consequent lessening in the 60 rate at which the refrigerant is expended.

I find that by cooling the air through the use of tubes 21 in the manner described I am able to likewise control the relative humidity of the air, thereby preventing an oppressive increase in 65 the moisture content of the air upon a lowering in the temperature. It will be apparent from Figs. 1 and 4 that the use of a plurality of tubes 21 arranged as shown, provides a very large surface which the air may contact during its passage through the cabinet. As the temperature of the air falls, the saturation point for the lower temperature is reached, with resultant condensation of moisture on the walls of tubes 21. I find that this condensation is sufficient to prevent the 75

air from becoming excessively humid even where the temperature drop is as much as 40° F. In order to remove the condensed moisture from tubes 21 I arrange the latter in inclined position as shown in Fig. 4. With the tubes in this position the moisture will drain toward the forward ends of the tubes, and will then flow downwardly along wall 7 into a drip pan 49, which is placed below the cabinet. The condensed moisture is thus automatically removed from the path of air flow and I am able to keep the air comparatively dry regardless of the temperature to which it is cooled.

The invention provides a cooling unit which is comparatively cheap in that it does not require the use of the costly compressor-condenser mechanism which is used in mechanical refrigerating apparatus. It finds an important field of use in the cooling of offices and similar places which perhaps would require air conditioning only for a comparatively short time during the summer months. Under such conditions the outlay required for a mechanical refrigerating unit would be prohibitive.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. Air conditioning apparatus comprising, in combination, a cabinet, a plurality of air flow tubes extending transversely through said cabinet near the bottom thereof, the lower portion of the cabinet enclosing said tubes being adapted to hold a body of liquid extending to a level above the uppermost of the tubes, means for supporting a mass of a solidified refrigerant in the cabinet above said tubes and in position to be partially submerged by the liquid contained in the lower portion of the cabinet, and means for regulating the extent of immersion of the mass of refrigerant in said liquid.

2. Air conditioning apparatus comprising, in combination, a cabinet, a plurality of air flow tubes extending transversely through said cabinet near the bottom thereof, the lower portion of the cabinet enclosing said tubes being adapted to hold a body of liquid extending to a level above the uppermost of the tubes, means for supporting a mass of a solidified refrigerant in the cabinet above said tubes and in position to be partially submerged by the liquid contained in the lower portion of the cabinet, and means comprising a vertically movable fluid displacing member for varying the level of liquid in the cabinet whereby to regulate the extent of immersion of said mass of refrigerant in the liquid.

3. Air conditioning apparatus comprising a receptacle having a plurality of air flow tubes extending transversely therethrough, means for supporting a mass of a solidified refrigerant in said receptacle above said tubes, a body of liquid disposed in said receptacle around the tubes and in contact with a portion of the mass of refrigerant, the freezing point of said liquid being below the melting point of the refrigerant, and

means for regulating the extent of immersion of the refrigerant in said liquid.

4. Air conditioning apparatus comprising, in combination, a cabinet, a plurality of air flow tubes extending transversely through said cabinet near the bottom thereof, the lower portion of the cabinet enclosing said tubes being adapted to hold a body of liquid extending to a level above the uppermost of the tubes, and means for supporting a mass of solid carbon dioxide in the cabinet spaced above the uppermost of said tubes and in position to be partially submerged by the liquid contained in the lower portion of the cabinet.

5. Air conditioning apparatus comprising, in combination, a cabinet, a plurality of air flow tubes extending transversely through said cabinet near the bottom thereof, the lower portion of the cabinet enclosing said tubes being adapted to hold a body of liquid extending to a level above the uppermost of the tubes, means for supporting a mass of solid carbon dioxide in the cabinet spaced above the uppermost of said tubes and in position to be partially submerged by the liquid contained in the lower portion of the cabinet, and means for circulating the air to be treated through said tubes.

6. Air conditioning apparatus comprising a receptacle having a plurality of air flow tubes extending transversely therethrough, means for supporting a mass of solid carbon dioxide in said receptacle spaced out of contact with said tubes, a body of liquid disposed in said receptacle around the tubes and in contact with a portion of the mass of refrigerant, the freezing point of said liquid being below the melting point of the refrigerant, and means for circulating the air to be treated through said tubes.

7. Air-conditioning apparatus comprising: a cabinet, a plurality of air-flow tubes extending transversely through the lower region of said cabinet, a refrigerant chamber being formed above said tubes, said chamber being closed on all sides and at the top, and of such dimensions as to receive a mass of carbon-dioxide ice and provide a closed space around all sides of and above said mass, means to support said mass above and out of contact with said tubes, and means for withdrawing the vapor, resulting from vaporization of said mass, from the upper region of said chamber, the region of said cabinet below said chamber being adapted to hold a body of liquid extending to a level in contact with the bottom of said mass, forming the bottom of said closed space in which said vapor is confined in the form of an insulating blanket enveloping all sides of said mass except its bottom.

8. Air conditioning apparatus comprising, in combination, a cabinet, a plurality of air flow tubes extending transversely through said cabinet near the bottom thereof, the lower portion of the cabinet enclosing said tubes being adapted to hold a body of liquid extending to a level above the uppermost of the tubes, and means for supporting a mass of solid carbon dioxide in the cabinet spaced out of contact with said tubes and in position to be partially submerged by the liquid contained in the lower portion of the cabinet.

BERT E. MILLS.
